Houson & Houson

UNITED STATES PATENT OFFICE.

LINCOLN VAN GILDER, OF VENTNOR, NEW JERSEY.

VALVE-BOX.

1,377,105.

Specification of Letters Patent.

Patented May 3, 1921.

Application filed July 3, 1917. Serial No. 178,458.

To all whom it may concern:

Be it known that I, LINCOLN VAN GILDER, a citizen of the United States, residing in Ventnor, Atlantic county, State of New Jersey, have invented a Valve-Box, of which the following is a specification.

One object of this invention is to provide a manhole cover, valve box or similar structure of novel form, characterized among 10 other features, by the inclusion of a lid having a plurality of annular shoulders or offsets and a body provided with an opening formed with a multiple-step edge for the reception of said lid;—the invention also 15 contemplating the use of recesses so placed in the edge of the body opening as to permit of the insertion of a lever or bar for the purpose of loosening and raising the lid.

It is further desired to provide a box or 20 cover of the type noted which in addition to being particularly adapted to sustain heavy loads, shall be so formed as to be capable of convenient extension or shortening to permit of its use with valves or other devices 25 set in the ground at widely varying depths.

I also desire to provide a manhole cover or valve box with a novel form of multiple water and sand seal for its lid in which the parts shall be so formed as to facilitate the 30 quick and convenient removal of said lid.

These objects and other advantageous ends I secure as hereinafter set forth, reference being had to the accompanying drawings, in which,

35 Figure 1 is a longitudinal vertical section of a valve box constructed according to my invention;

Fig. 2 is a plan of the top of the box shown in Fig. 1;

40 Fig. 3 is a vertical longitudinal section of the top element of a slightly modified form of the invention; and

Fig. 4 is a modified top plan applicable to the structures shown in either of Figs. 45 1 or 3.

In the above drawings 1 represents the tubular top section of a valve box or man-hole cover constructed according to my invention, which includes a substantially circular body 3 and a top flange 2, having in the case of Fig. 1, a square outline, although obviously it may have a generally circular or other form, with any desired number of projections as indicated at 2^a in Fig. 4.

55 Below this top flange the body is provided with a second flange 4 which may be con-

nected to said top flange by two or more vertical webs 5. The opening in the upper end of the body is formed to provide two concentric flat horizontal shoulders or offsets 6 and 7 for the reception and support of a lid 8, whose edge is of stepped section to provide two flat faces designed to respectively rest upon the two faces of the shoulders 6 and 7. Said lid has a central annular 60 extension 8^a designed to fit closely inside of the top of the body 3, it being noted that this extension as well as the edges of both of the shouldered parts 9 and 10 of the lid, are tapered or inclined as shown. 70

In order to facilitate the removal of the lid from the body, I form the top flange 2 thereof with any suitable number of radially extending recesses or cavities 11 which extend downwardly to the level of the lower 75 shoulder 6 and under the part 10 of the edge of the lid. When four of these recesses are employed, the top flange 2 is given the square outline shown in Fig. 2, with one of the recesses in each corner, while if but two 80 recesses are employed, the flange is made generally circular as at 2^a in Fig. 4, and has two oppositely extending angular extensions in which its recess 11 are formed.

The lower part of the body 3 is preferably 85 extended or given a bell-mouthed form as indicated at 12, and immediately above this portion is provided with an annular groove 13 or is otherwise made structurally weak in order to permit of the convenient breaking 90 away and removal of said bell-mouthed end when this is advisable.

Under conditions of use the structure 1 is preferably employed in connection with a pipe or tubular structure 14 having its lower 95 end extended or given a bell-mouthed form as indicated at 15 and provided with an outwardly projecting flange 16. In order to render the part 14 conveniently adaptable to the different conditions, it is provided with 100 any desired number of annular curved or weakened portions 17 and 18.

These upper and lower parts 1 and 14 are preferably employed in connection with an intermediate tubular section 19, which may 105 customarily consist of a suitable length of scrap pipe of such diameter as to fit into the bell-mouthed lower end 12 of said section 1 and also fit over or into the upper end of the lower section 14. Obviously by 110 breaking or cutting off one or more of the upper sections of the part 14, and using it

either with or without the intermediate parts 19 and 12, the apparatus may be suited for use in connection with valves or other apparatus set at widely varying depths.

5 In an extreme case the intermediate part 19 may be omitted, the bell-mouth 12 and the upper sections of the part 14 may be broken off and the reduced diameter portion of the upper end of the bottom bell-mouth 10 15 may be fitted directly into the lower end of the body 1.

It should be noted that while the particular structures illustrated in the drawings have been designed to serve as valve boxes for protecting and providing access 15 to valves situated below the level of the sidewalk or street, the upper part thereof may be advantageously employed as part of a manhole construction. One important 20 feature of this top portion resides in the second or lower flange 4 which when the box is used in the street, may be embedded in or set on the concrete or other foundation of the roadway, thereby effectually supporting 25 the upper portion of the structure and preventing its being driven down or displaced when exposed to heavy traffic.

In that form of the apparatus shown in Figs. 3 and 4, the tubular body is made in 30 two parts 1^a and 1^b of which the first is of relatively small diameter and receives within its upper end the central annular part 8^a of the lid, while the second part 1^b is of increased diameter and projects down from 35 the middle of the under face of the flange 4. This form of the invention is adapted for use where the valve to be protected or rendered accessible is relatively near the surface or where an increased space for manipulation is required below the flange 4. When the part 1 of my device is to be used 40 as a manhole cover, that part of the tubular body below the flange 4, may if desired, be omitted without departing from the invention.

45 I claim:—

1. The combination in a device of the character described of a tubular body having on one end a plurality of annular shoul-

ders of different diameters; with a lid having 50 an edge of stepped section including a plurality of annular bearing faces placed to engage the shoulders of the body respectively, the top of said body having at least one radial recess extending to a depth sufficient to give access to one of the bearing faces of the edge of the lid.

2. The combination in a device of the character described of a tubular body having on one end a plurality of annular shoulders of different diameters; with a lid having 60 an edge of stepped section including a plurality of annular bearing faces placed to engage the shoulders of the body respectively, the top edge of said body having 65 projecting portions formed with recesses open to the interior of the body and deeper than the uppermost shoulder thereof so as to give access to one of the bearing faces of the lid.

70 3. The combination in a device of the character described of a tubular body having a flange at one end and formed with a plurality of annular shoulders of different diameters providing flat bearing surfaces; and a lid with an edge of stepped sections having a plurality of annular bearing portions placed to engage the flat portions of the body, there being radially extended recesses in the flange of the body positioned to 80 give access of a lid raising tool to an overhanging portion of said lid.

75 4. The combination in a device of the character described of a tubular body having a flange at one end; a second flange 85 spaced away from said end; substantially radial webs extending between and connecting said flanges, the end of the body adjacent the first flange being formed to provide a plurality of annular shoulders having flat bearing surfaces; with a lid having an edge of step section and including flat annular faces formed to coact with the flat faces of the shoulders, said first flange having substantially radial recesses extending 90 under one of the annular faces of the lid.

95 In witness whereof I affix my signature.

LINCOLN VAN GILDER.
